UNITED STATES PATENT OFFICE.

EZRA S. BUCKNAM, OF PHILADELPHIA, PENNSYLVANIA, ASSIGNOR TO
JOHN A. BRILL, OF PHILADELPHIA, PENNSYLVANIA.

CAR.

No. 800,717.

Specification of Letters Patent.

Patented Oct. 3, 1905.

Application filed December 17, 1904. Serial No. 237,243.

To all whom it may concern:

Be it known that I, EZRA S. BUCKNAM, a citizen of the United States, and a resident of the city and county of Philadelphia and State 5 of Pennsylvania, have invented a new and useful Improvement in Cars, of which the following is a specification.

The object of my invention is to improve cars, and more particularly those with large 10 windows, such as are commonly used in street traffic. The windows of such structures now in common use have lugs or trunnions protruding from the edges of the sashes into grooves of a curved and irregular nature, which 15 grooves determine the movement of the sashes. A car with windows of this nature was patented jointly by John A. Brill and myself, the United States patent being numbered 709,073, and it is obvious that there 20 are many other kinds of cars to which the foregoing applies with equal force, as it has been the fixed and invariable practice for a number of years to guide straight sashes in curved and irregular grooves by means of trunnions or pintles in the edges of the sashes. 25

By my improvement I do away with all trunnions and grooves and substitute a peculiar sash construction which slides on certain guide-rails, which are suitably fixed, so 30 that the sashes are suspended below.

It is obvious that this improvement may be used on other structures than cars, so that I do not regard it as limited thereto, but as being commensurate with all structures to 35 which it is applicable.

For a more particular description of my improvement reference is to be had to the accompanying drawings, forming a part hereof, in which—

40 Figure 1 is a sectional view showing a section of a side of a car provided with my improvement. Fig. 2 is a detailed view showing a portion of the sashes detached from the frame. Fig. 3 is an enlarged view of the upper portion shown in Fig. 1. Fig. 4 is a perspective view of a portion of the structures of the upper sash and roof. Fig. 5 is a perspective view of a portion of a post and adjacent sashes. Fig. 6 is a sectional view showing a 45 stop secured to an upper sash and a portion of a guide-rail. Fig. 7 is a perspective view of a lower-sash lock and a small portion of the sash. Figs. 8 and 9 are perspective views of the upper and lower sashes, respectively, 50

of each window. Figs. 10 and 11 show the top catch-plate, Fig. 11 being taken on the line 11 11 of Fig. 10 looking in the direction of the arrows. Figs. 12, 13, and 14 show intermediate catch-plates, Fig. 13 being taken on the line 13 13 of Fig. 12. Fig. 15 shows 55 wedge-plates, one adapted to be secured to a window-frame, the other to a lower sash. Fig. 16 shows a portion of a post and parts of adjacent sashes. Figs. 17 and 18 are sectional views taken on the lines 17 17 and 60 18 18, respectively, of Fig. 16. Fig. 19 is a perspective view of a portion of an upper sash. Fig. 20 is a perspective view of a cam-wedge secured in a portion of the window-frame. 70

Throughout the various views of the drawings similar reference characters designate similar parts.

While my improvement is applicable to a wide range of structures, it is more particularly adapted to cars with large windows, and therefore this construction is described, without, however, any prejudice to the scope of the claims, which should be construed as applicable to a window in any form of structure where the sashes are stored in an inclined position. 75

The window herein illustrated comprises the frame having the sill 1, posts 2, letter-board 3, and the sashes 4 and 5. When the 80 window is opened, the sashes 4 and 5 are stored between the roof 6 and ceiling or head-lining 7, as will appear below. Only a small portion of the car construction is herein described, as this is ample to enable those 85 skilled in the art to practice my invention.

The posts 2 extend from the car-sills 8 to the roof 6, which is supported in the conventional manner. The lower portion of the space between the posts 2 is closed by a fixed 90 panel and the extreme upper portion by the letter-board 3. When the window is closed, as shown in Fig. 1, the lower sash 5 rests on the sill 1 between the posts 2, and its edges are held between the outer guide-strip 9 and the inner guide-strip 10, and the sash 5 is locked in place by any suitable sash-lock 11, the preferred form being shown. 95

The sashes 4 and 5 are pressed together by means of wedges 12 and 13, which are placed 100 slightly below where these sashes overlap, the wedge 12 being fixed to the strip 10 and the wedge 13 being fixed to sash 5. These

wedges 12 and 13 cause the sashes to engage with a weather-tight joint. When in the lowest position, the sash 4 rests on cams 14 with stops 15, the lower ends of the sash 4 being recessed at 16, so as to fit these cams 14, as shown in Figs. 8 and 19. The function of the cam 14 will appear below.

Each of the sashes 4 and 5 are what are known as "metal" sashes—that is, the top and bottom of each sash are made of wood; the sides are made of angle metal, preferably brass, filled with wood, as appears in Figs. 17 and 18, as well as elsewhere. The metal strip 17 of the lower sash 5 is bent inwardly at 18 to form a groove in which slides a guide-flange 19, which is fixed to each edge of the frame of the sash 4. This guide-flange 19 is fixed to the metallic part 20 of the sides of the sash 4 and the flanges 19 on opposite edges of a sash are parallel to each other, but not quite parallel to the plane of the sash—that is, the upper end of the flange 19 is more remote from the part 20 than is the lower end, so that as the sash 5 is raised its upper end is guided away from and out of contact with the sash 4, and when lowered the sashes are brought close together until they finally engage where they overlap with a weather-tight joint. The movement of the upper portion of the sash 5 is determined by the flanges 19 and grooves 18 and the lower portion by the strips 9 and 10.

Secured to the upper edges of each upper sash are stops 21, arranged in pairs on each sash. These stops 21 each have a shoulder 22, against which the upper edge of the sash 5 impinges when raised sufficiently, and this shoulder 22 is connected to the sash by parallel uprights 23, which uprights are united by a web 24, having a dowel-pin 25 and screws 26. Extending from the web 24 and riveted thereto is the spring 27, the upper end of which is recessed and provided with an antifriction-roller 28, which turns on a pin 29. The uprights 23 are further united by means of a pin 30, on which is a second antifriction-roller 31. A guide-rod 32 is fixed to the letter-board 3 and extends upwardly in a direction substantially parallel to the roof of the car to a point close to the usual monitor top or decking of the car or top of the car if such decking is not provided. While the rail 32 may be given any suitable form, it is preferably substantially rectangular in cross-section, as shown in Fig. 4, and the lower end is so shaped that the sash 4 is forced snug against the letter-board 3 when the window is closed, and the upper end of the rail 32 is preferably bent, so as to be secured between the head-lining 7 and top rail 33, as shown in Fig. 3. The stops 21 surround the free guide-rail 32 and act as hangers to support and guide the upper ends of the sashes 4 and 5 when raised.

To the top rail 34 of the sash 5 are secured

stops 35, each of which has a projecting tongue 36, which is adapted to extend over and rest on the lower rail 37 of the sash 4. These tongues 36 enable the sash 5 to positively control the downward movement of the sash 4 should such positive control be necessary.

In order to enable the window to be conveniently opened any desired amount, the posts 2 on each face next the sashes are provided with suitably-located sockets 38, 39, and 40, which are sunk to be flush with these surfaces of the posts 2 and are located as follows: The sockets 38 are placed next the cam and stops 14, the socket 39 is slightly above this, as shown in Fig. 1, and the socket 40 is at the upward limit of the movement of the sash-lock 11, the bolt 41 of which is adapted to enter any of the above-mentioned sockets 38, 39, and 40, as desired, as well as a socket 85 of the conventional form (not shown) when the sash 5 is in its lowest position. For convenience the upper walls of these sockets are inclined, so that the bolt 41 will be drawn gradually to its proper seat should the sash 5 be raised too high.

From the foregoing the operation of my improvement will be readily understood. When the sash 5 is raised after releasing the bolt 41 of the sash-fastener 11, the lower end of the sash is guided between the strips 9 and 10 and the upper end by the guide-flanges 19, which engage the walls of the grooves 18, as above described. This continues until the stop 35 on the top rail 34 engages with the stop 22, and then if the movement be continued the sashes 4 and 5 move together as a unit, and their united upper ends are guided by the stops 21, sliding on the rails 32, the antifriction-rollers 105 preventing abrasion or undue friction, and the spring-tongue 27 permits the distance between the rollers 28 and 31 to vary to accommodate itself to the different angles made between the axles of the stop 21 and the rail 32. After the catches 11 pass the wedge 12 the lower end of the sash 5 no longer rests firmly between the strips 9 and 10, because the distance between these strips is increased to permit these sashes 4 and 5 to become inclined, so as to rest between the head-lining 7 and roof 6. The bolt 41 may be placed in any of the sockets 38, 39, or 40, as desired, depending upon the amount the window is to be opened. If in the socket 120 40, the sashes will occupy the position indicated in Fig. 3 by dotted lines. The windows are lowered from this position by releasing the bolt 41. If the lower edge of the sash 5 slides against the strip 9 on this downward movement, the cam-wedge will cause it to move over into its proper place in the groove between the strips 9 and 10, so that it is impossible for the sash 5 to be stopped by the stop 15, and this downward movement of 125 130

his sash is had without hindrance. These results are obtained without pintles or pine-grooves, so that a more simple and efficient arrangement is effected by my invention. While I have shown and described the embodiment thereof, it is obvious that many others may be made that employ its essential features, so that it should not be regarded as limited to this disclosure, but as broad enough to cover all structures that come within the scope of the annexed claims.

Having thus described my invention, what claim is—

1. In a device of the class described, stanchions, and a roof, free guide-rails supported immediately under said roof and adjacent thereto, a sash below said rail and means for suspending said sash from said rails.

2. In a device of the class described, a window provided with the usual frame, a free guide-rail secured above said window and within the car, and a sash suspended from said rail.

3. In a device of the class described, a window-frame, a free guide-rail secured adjacent thereto, a sash and a stop fixed to said sash and provided with antifriction-rollers that engage said rail.

4. In a device of the class described, a window-frame, a guide-rail secured adjacent thereto, a sash and a stop fixed to said sash and antifriction-rollers secured to said stop and adapted to bear against said rail, one of said rollers being spring-mounted.

5. In a device of the class described, a window-frame, a free guide-rail adjacent thereto, a plurality of sashes with means for connecting them together so that one may slide relatively to the other or others and means for hanging one of said sashes from said rail.

6. In a device of the class described, a window-frame, a guide-rail adjacent thereto, a plurality of sashes with means for connecting them together so that one may slide relatively to the other or others and a stop secured to one sash and slidably mounted on said rail.

7. In a device of the class described, a window-frame, a guide-rail adjacent thereto, a plurality of sashes with means for connecting them together so that one may slide relatively to the other or others, a stop secured to one sash and slidably mounted on said rail and wedges with coöperating surfaces, one of said wedges secured to said sash and the other to said frame whereby the sashes are forced together to form a tight joint between them.

8. In a device of the class described, a window-frame, a guide-rail adjacent thereto, a plurality of sashes with means for connecting them together so that one may slide relatively to the other, a stop secured to one sash and slidably mounted on said rail and means

on said frame and one sash for forcing said sashes together to make a tight joint.

9. In a device of the class described, a window-frame, a guide-rail adjacent thereto, a plurality of sashes with means for connecting them together, a stop secured to one sash and 70 slidably mounted on said rail, and a cam-wedge fixed in said frame and adapted to shift one sash into its proper place when it is lowered and not to interfere with the other sash.

10. In a device of the class described, a window-frame, a guide-rail adjacent thereto, a plurality of sashes with means for connecting them together, a stop on one sash which is slidably mounted on said rail, a cam-wedge 80 adapted to control the movement of the lower edge of one sash and a fastener-receiving recess with flaring walls adjacent to said cam-wedge.

11. In a device of the class described, a window-frame, guide-rails adjacent thereto, stops suspended from said rails, a sash suspended from and fixed to said stops, guide-flanges fixed to said sash, and a second sash having a sliding movement determined by 90 said flanges.

12. In a device of the class described, a window-frame, a sash adapted to slide therein, means for determining the movement of said sash, guide-flanges fixed to said sash, a 95 second sash whose movement is determined by said flanges and grooves in said second sash into which said flanges protrude.

13. In a device of the class described, a window-frame, a sash mounted to slide in 100 said frame, said sash being provided with parallel guide-flanges which run at a slight angle to the plane of the face of the sash, a second sash and means in the edges of said second sash to engage said guide-flanges.

14. In a device of the class described, a window-frame, a sash mounted to slide therein, parallel flanged guides at each edge of said sash, said guide running at a slight angle to the plane of the sash, a second sash 110 adapted to engage said guides and slide between them, and wedges on said frame and second sash for causing the sashes to engage with a tight joint when the window is closed.

15. In a device of the class described, a window-frame, a sash mounted to slide therein, parallel and flanged guides at each side of said sash, said guides running at an angle to the face of the sash, a second sash whose movement is determined by said guides, and a stop on said second sash for limiting its movement in one direction with regard to the first sash.

Signed this 15th day of December, 1904.
EZRA S. BUCKNAM.
